NEEDLE BUTT PULLER

Harold M. Smith, Greensboro, N. C.

Application October 19, 1937, Serial No. 169,852

2 Claims. (Cl. 254—104)

The object of my invention is to provide an improved needle butt puller for use on knitting machines for removing the butts of broken needles without necessitating removal of the needle plate 5 from the machine, as has been the usual and necessary custom heretofore.

It is also an object of my invention in having a novel adjustable hook end which permits of its being adjusted to operate in a minimum space 10 and at angles that the old needle butt puller was not adapted to operate whereby much time will be saved to the operator in replacing broken needles. As most of the knitters work on piece work basis, any saving of their time is, of course, 15 to their financial advantage as well as to the advantage of the operator of the factory.

I attain the objects of my invention by the device illustrated in the accompanying drawings, in which—

20 Figure 1 is a front plan view of the invention; Fig. 2 is a side or edge view of same;

Fig. 3 is a side or edge view showing the method of using the implement at the outset of the operation of removing the broken needle butt;

25 Fig. 4 is a similar view showing the needle butt as it is being pushed out from its socket by the implement; and—

Fig. 5 is a view of the method of extracting the needle butt after it has been partly pushed out 30 from its seat.

Like characters of reference designate like parts in each of the several views.

Referring to the accompanying drawings there is illustrated a portion of the knitting machine, 35 namely, the base 1, an upright portion of needle bar 2 carrying a needle plate bolt 3. Affixed to the portion 2 of the needle bar is the needle carrying plate 5 from which depends a strip 6 which functions as a socket for the shank or butt of the 40 needle end. 7 designates the needle plate the lower end of which is adapted to seat in the recess 4 of needle bar 1, the upper end of the needle plate being designated 8. Needle butt puller 10 has an enlarged portion 9 at its center and at 45 one end has a hook 12 adjustably connected by screw 11 to the other end of member 10. The function of the enlarged portion 9 of the implement is to facilitate grasping and operating it. The arrows in Figs. 3, 4, and 5 indicate the

direction of operation of the implement. The hook 12 has an offset end portion 13 to engage the end of the needle butt. The needle butt puller has a slightly curved split or bifurcated end 14, each leg of said bifurcated end being slightly 5 rounded at its foot, as shown in Fig. 1.

In use the needle butt puller is inserted in the manner shown in Fig. 3 with the hook end 12 in position so that its offset end 13 can be pressed against the butt end of the needle and to force 10 it out of the strip of metal or socket 6. A needle always breaks at the bent portion, as indicated in Fig. 3. When the needle butt has been pressed outwardly, as shown in Fig. 4, the implement may then be withdrawn and reversed and its 15 split end 14 engaged on the needle to pull it out very much as a tack is lifted out with a tack puller, as shown in Fig. 5.

The main object of this new type of needle 20 butt puller is its adaptability to any angle necessary to get in behind a needle butt. The old needle butt puller which this invention super- 25 sedes is simply a hook and is large and cumbersome and requires more space for its use and is not adaptable to angles.

Knitting machines in connection with which 25 this implement is used are put up in sections and are some fifty feet long when assembled and may have from eighteen to thirty sections. Each needle bar holds some fifty needles closely spaced 30 in the needle bar one after the other. While good needles may be removed without the use of the needle butt puller, where the needles are broken off as they often are, it is necessary that the knitter use the needle butt puller in order to 35 extract the broken butt and replace it with a new needle.

What I claim is:

1. A needle butt puller comprising a bar having a hook end pivotally and adjustably affixed to one 40 end of the implement, said hook end having an offset portion to engage the projecting end of the broken needle butt.

2. A needle butt puller comprising a bar, and a hook end pivotally and adjustably affixed to 45 the other end of the implement, said implement having a widened center portion to facilitate grasping the implement for operating it.

HAROLD M. SMITH.
